[57] CLAIM

The ornamental design for a single fire ignition module, as shown.

DESCRIPTION

FIG. 1 is a top plan view of our invention;
FIG. 2 is a front elevation of our invention;
FIG. 3 is a right side elevation of our invention;
FIG. 4 is a bottom plan of our invention;
FIG. 5 is an isometric view of our invention taken from slightly above the device; and,
FIG. 6 is a bottom isometric view of our invention taken from slightly below the device.

FIG. 5

FIG. 1

FIG. 2

FIG. 3

FIG. 4

FIG. 6
